UNITED STATES PATENT OFFICE.

FRANCIS M. TURNER, OF NEW YORK, N. Y.

APPARATUS FOR AND PROCESS OF REFINING VEGETABLE AND OTHER OILS.

Application filed June 7, 1921. Serial No. 475,700.

To all whom it may concern:

Be it known that I, FRANCIS M. TURNER, a citizen of the United States of America, residing at New York city, county and 5 State of New York, have invented certain new and useful Improvements in Apparatus for and Processes of Refining Vegetable and Other Oils, of which the following is a full, clear, and exact description.

10 This invention relates to improvements in the process of refining oils, more particularly vegetable oils, such as oil from cocoanut, cotton seeds, copra, sesame seeds, or in fact any oils containing fatty acids. Many 15 methods have been devised to obtain edible oils from the above elements with more or less success. So far as I am aware, the methods commonly used are carried out in the presence of air, that is to say, the various 20 steps of the processes are performed in receptacles containing air, and hence the oil at all times is under the influence of oxygen and becomes oxidized.

With my improved process, the various 25 steps are carried out under a high vacuum, that is to say, the receptacles within which the steps are carried out are under a high vacuum during the entire refining process. I am thus able to prevent oxidization, especially during the neutralizing and decolorizing steps. When oils containing fatty acids are neutralized, under present 30 approved methods, an alkali is introduced to neutralize the fatty acids and when the 35 oil is to be used for edible purposes, it is desirable to remove both alkali and neutralized fatty acids and to this end it is desirable that the neutralized acid form with the alkali insoluble salts of greater specific 40 gravity than the oil so that the oil can be decanted from the salts. When a sodium compound is used as an alkali, the reaction results in anhydrous insoluble salts, but the presence of air and moisture carried by the 45 air results in oxidation and emulsification of the oil with a portion of the neutralized acids, forming a soda soap which is deleterious to edible oils. My process is to remove the air with its moisture during the 50 neutralizing, whereby substantially all the neutralized acids are precipitated in insoluble salts and also, by decanting in vacuum, I remove these salts in the absence of moisture laden air. Then during the further 55 treatment, I prevent whatever neutralized acid remains from contaminating the oil,

which treatment, while especially for the customary steps of bleaching and deodorizing, serves also under my process for the further removal of these neutralized acids. 60 Thus unprecipitated finer salts and incomplete reactions will be recovered during the later treatments while still free from the deleterious contamination. To accomplish this, I carry out the entire refining process 65 under vacuum and preferably a very high vacuum. To this end I have improved the method of separating the filter material from the oil which serves also better to remove the residue of these neutralized acids. 70 This improvement is to provide a centrifuge operating inversely to the centrifuges commonly used for separating granules from liquids. In this centrifuge, I drive the granules into pockets upon the exterior walls 75 and direct the liquid internally over the pockets thus retaining in the pockets all granules whether of greater or less specific gravity than the oil. Even though this and the preceding steps are superior to the previous methods, there still remains volatile fatty acids which would in the air cause saponification and so I carry the vacuum through the volatilizing process and withdraw the volatilized acids by this process. 80 Should saponification take place, it means that the entire batch is ruined for the production of edible tasteless or odorless oils. The intent of the neutralizing step is to remove all fatty acids and soda-soap, but if 85 there is any moisture present it is almost impossible to remove the soda soap, and furthermore, it takes considerable time to effect the neutralization. To produce a perfect 90 edible oil, it is essential that all of the soap be removed.

In my improved process, the neutralization is carried out in vacuo, thereby avoiding any untoward action of oxygen. By carrying out this step in vacuo, the resultant 100 soda-soap becomes anhydrous and insoluble, rendering the separation thereof from the oil an easy matter.

As the neutralizing step in my improved process is carried out under high vacuum, 105 the danger of formation of emulsions caused by saponification is reduced to a minimum. Furthermore, I am able to carry out this step in very much less time than if the step is carried out in the presence of air, and 110 hence at less expense. Before the neutralizing step takes place, I first compute the

amount of fatty acids contained in the oil to be removed, and then combine with the oil the correct amount of caustic soda solution of a certain specific gravity, the mixture being then placed in a neutralizing tank, to be hereinafter described.

After the neutralizing step is performed, the treated oil is introduced into a decanting tank, within which the oil and anhydrous soda soap is separated. After the oil and soda soap have been introduced into the decanter or decanters, the soda soap will settle in the bottom thereof, leaving the oil free.

15 After the decanting step, I introduce the oil into a tank for the purpose of decolorization. To decolorize the oil, I employ fuller's earth, filtchar or a specially prepared carbon (lignite carbon). The decolorizing step 20 will also be conducted under high vacuum, which will prevent oxidization of the oil, which is very important. After the oil is decolorized, it will be passed through filter press, or centrifugal separator, to remove 25 the fuller's earth, (or other decolorizing agents), which has been rendered anhydrous, owing to the fact that a high vacuum has been present during the decolorizing step, which eliminates moisture.

30 After the decolorizing step, the oil will be introduced into a purifying tank or tanks under high vacuum of approximately 29.72 in. when the atmospheric pressure is 29.92 in., and subjected to steam produced from 35 distilled water in a generator which is under vacuum.

From the purifiers the steam and oil are introduced into a separator to separate the oil and steam, the steam being condensed 40 and conveyed to the steam generator, and the oil being conducted into a cooler. The steam flows into a rotary vacuum condenser, where it becomes condensed and at the same time produces the high vacuum desired.

45 It will be apparent that the entire process is carried out under a high vacuum, whereby the soda-soap in the oil, which has been neutralized, and the fuller's earth or other agent used in the decolorizing step is rendered anhydrous and hence easily separated from the oil. Furthermore, as the steam used in the purifying step is generated under vacuum, it will be produced from water, which will boil, at about 72 degrees Fahrenheit, as said water will be under a vacuum of approximately 29.72 in. when the atmospheric pressure is 29.92 inches; hence the temperature of the steam will be relatively low or in other words, from 113 degrees to 55 140 degrees Fahrenheit; therefore, the delicacy of the flavor of the oil will be retained.

The process as above outlined is applicable to oils such as cocoanut, cotton seed, etc., containing fatty acids, which have to

be neutralized. With some oils, such as first grade peanut and olive oils, neutralization is not required.

My improved process is intended to refine clarified crude oils, that is to say, oil from which the foots and mucilage have already been removed. This clarified oil contains fatty acids, coloring matter and other substances which must be removed to render it bland and free from taste, odor, and where desirable, color.

One of the most important features of my invention is that all of the steps are carried out in high vacuo, to prevent the presence of oxygen, thus avoiding hydrolysis, 80 and also to render the soda-soaps anhydrous and the decolorizing agents more active. Owing to the fact that the soda soap is rendered anhydrous, it can be more easily separated from the oil, than if it remained in 85 the natural state in the presence of air and moisture; hence, a more perfect oil can be obtained.

In carrying out my improved process, I employ an apparatus illustrated in the accompanying drawings, wherein:—

Fig. 1 illustrates a series of interconnected tanks and vacuum apparatus; and

Fig. 2 illustrates diagrammatically a centrifugal separator.

To carry out my improved process, I employ a tank 1 within which the first step of the process is carried out, namely, neutralization. The tank 1 contains stirrers 2, mounted on a rotatable shaft 3 driven by a belt 4 and a pulley 5. The shaft 3 also extends into an adjacent tank 6 in this instance, and carries stirrers 7 similar to stirrers 2. The tanks 1 and 6 are, in this instance, supported by standards 8 and are fixed, or in other words, do not rotate. The clarified crude oil is placed in tank 1, mixed with the proper amount of the neutralizing agent, through the manhole 9 and agitated by the stirrers 2, the shaft 3 being caused to rotate after the tank has been charged. At the proper time a gate valve 10 in the duct 11, will be opened and the treated oil and extracted soda soap will be allowed to flow into the decanting tank 12, and allowed to remain until the soda soap, which has been rendered anhydrous, during the first step in the operation, settles into the bottom 13 of tank 12. After the soda soap has settled, the oil in tank 12 will be pumped by means of a centrifugal pump 14, into a tank 6, wherein the oil will be decolorized. After the oil has been delivered to tank 6, the proper amount of fuller's earth, filtchar or a specially prepared carbon (lignite carbon) will be introduced into said tank through the manhole 15. After the oil in the tank 6 has received its charge of the decolorizing agent, shaft 3 will be again rotated to cause the stirrers 7 to agitate the mixture. At the 130

proper time the rotation of shaft 3 will be stopped and valve 16 in duct 17 will be opened, allowing the contents of tank 6 to flow into a filter press 18 located within an air-tight chamber 19. After the decolorized oil has been introduced into the filter-press, the plates thereof, indicated by 20, will be forced together by the threaded spindle 21 which carries a hand-wheel 22 (in this instance), but said spindle may be power driven if desirable. After the oil and decolorizing agent have been separated by the press, the oil will flow into a tank 23 thereunder, from which it is taken, by a centrifugal pump 24, and delivered to purifying tanks 25 and 26, through duct 27.

In connection with the tanks 25 and 26, I employ means to introduce steam into the oil within the said tanks. To introduce steam into the oil, I locate in each tank, a steam spraying device 28 connected by a duct 29 to a generator 30 containing a steam coil 31. Steam will be generated by the coil 31 from distilled water, indicated by 32, and introduced into the oil in tanks 25 and 26, under pressure, through the duct 29 and spraying devices 28. After the oil has been purified, it will be drawn off through ducts 33 and 34 and allowed to flow into tanks 35 and 36, containing coils 37 for cold water.

As has been stated, all of the steps above mentioned will be carried out while the tanks are under vacuum, said vacuum being effected preferably by means of a suitable vacuum producing apparatus indicated by 38. The apparatus 38, which acts to effect a vacuum, is of a well known type operated by a steam jet, which flows into the chamber thereof through a duct 39 and out

through an outlet 40. The steam within the purifiers will be drawn therefrom by the vacuum device 38 into a separator or tank 41. Any oil which may be carried off by the steam will be precipitated when it reaches tank 41, and can be drawn therefrom through the cock 41^a in the bottom of the said tank. The pump will be operated by steam introduced thereinto through the duct 39 from a source not shown. The cooling tanks 35 and 36 will be connected to the vacuum line by ducts 47 and 48; hence, the oil will be cooled under vacuum. Throughout the entire process, the oil will be out of contact with any air.

In combination with the neutralizing tank 1 and decolorizing tank 6, I prefer to employ heating coils 50 and 51, one in each

tank to heat the oil while under treatment in said tanks. The coils 50 and 51 will be preferably heated by steam generated in generating tank 30.

Instead of a filter press, I may employ a centrifugal separator 50 of the Resines type, to separate the oil and decolorizing agent.

Having described my invention, what I claim and desire to secure by Letters Patent is:—

1. A step in the process of refining crude vegetable and animal oils and fats and of removing anhydrous soap therefrom which consists in subjecting the oil or fat to be neutralized to the action of a neutralizing agent to remove the free fatty acids therefrom while under vacuum, and removing therefrom all the moisture so that the oil and resultant soap are anhydrous whereby the soap is insoluble in the said oil or fat.

2. The combination of a tank for neutralizing oils, a settling tank connected therewith, means to deliver the contents of the neutralizing tank to the settling tank, a decolorizing tank, means to convey oil from the settling tank to the decolorizing tank, a filler press, means to convey the contents of the decolorizing tank to the filler press, a purifying tank, means to convey oil from the purifying tank to the purifying tank, a cooling tank, means to convey oil from the purifying tank to the cooling tank, and means to place all of said tanks under vacuum.

3. The method of separating soda soap from oils, which consists in mingling with the oil a sodium neutralizing agent and agitating the same while under high vacuum, whereby the soap is rendered anhydrous and then separating the soap from the oil.

4. The process of treating impure edible oils containing free fatty acids consisting in introducing the oily material into a closed system, producing and continuously maintaining a high vacuum throughout the system during all the steps of the process, neutralizing the free fatty acids with the correct mixture of alkali therefor, settling the mixture, decanting the oil from the soap formed, mixing the oil with decolorizing material, and filtering the mixture, thereby separating the oil.

Signed at New York city, N. Y., this 7th day of June, 1921.

FRANCIS M. TURNER.
